B. ROBINSON

CENTRIFUGAL SWITCH

Filed Dec. 24, 1923

Inventor

*Bid Robinson
Daniel F. Greenan.*

Attorney

UNITED STATES PATENT OFFICE.

BID ROBINSON, OF CHICAGO, ILLINOIS.

CENTRIFUGAL SWITCH.

Application filed December 24, 1923. Serial No. 682,573.

- The invention relates broadly to signaling devices and particularly to devices adapted to automatically break a circuit leading to the head and tail lights of an automobile 5 thereby putting out said lights and adapted to complete a circuit leading to the parking lights, when the car comes to a stop thereby simultaneously lighting the parking light, and shutting off the head lights.
- 10 Another object of the invention is to provide a signaling device arranged to automatically kill the engine as the car reaches a predetermined speed limit, thus providing a warning to help avoid violating speed regulations.
- 15 Another object of the invention is to indicate at the dash, by means of a plurality of colored lights or the like, the particular speed at which the car is running at that instant, without the aid of a speedometer.
- 20 Another object of the invention is to provide a device that may be set at the time of parking to kill the engine at a predetermined speed, to handicap by a low speed any unauthorized person trying to make a quick getaway.
- 25 Another object of the invention is to construct a device that is cheap of manufacture, compact and having a minimum number of working parts, all so arranged that they cannot be tampered with nor get out of order readily.
- 30 The foregoing and such objects and advantages as may be pointed out or appear as this description proceeds are attained in the structural embodiment illustrated in the drawings in which a preferred embodiment is shown wherein:
- 35 Fig. 1 is a vertical cross section through the device.
- 40 Fig. 2 is a cross section taken on lines 2—2 of Fig. 1.
- 45 Fig. 3 is a fragmental view showing a portion of the governor, shaft, insulator, contacts and associated parts drawn to an enlarged scale.
- 50 Fig. 4 is a longitudinal section taken through the insulator, disclosing the wire receiving passages.
- 55 The shaft 11 may be connected directly with the engine or any of its associated parts, arranged to revolve continuously while the engine is running.
- A housing is provided comprising two end sections 12 and 13 and a central section 14 on which aligned bosses are provided having registering central bores therein, through which extend bolts 15 to hold said sections securely together. The end sections 12 and 13 have cast integral thereon substantially centrally bored bosses 16 and 17 respectively. A bushing 18 is pressed or otherwise secured to the boss 16 and extends for the full length of the bore in said boss, while the boss 17 has a bushing 19 extending for a portion of the length of the hub 17, the remaining distance of said boss is counter bored and internally threaded to receive a guiding sleeve 21. The sleeve 21 is enlarged at one end for a short distance and externally threaded as at 22 to engage the threaded counter bore of the hub 17.
- The shaft 11 extends through the bushings 18 and 19 and the sleeve 21, and is lubricated through holes 23 in the bosses 16 and 17 which are tapped at one end, for the reception of oil cups or suitable oiling means.
- A tubular insulator 25, best illustrated in Fig. 4 is formed with a plurality of passage ways 26 extending for a distance longitudinally and then transversely outwardly to receive the current carrying wires, and to provide for the contacting engagement of the ends of said wires with a plurality of annular contacts. A plurality of rings 27 forming the annular contacts, are arranged over the insulator 25 separated by insulating rings 28 arranged to form spacers to dispose said contacts 27 at the desired distances relative to each other.
- A sectional rotatable slidable contact is mounted over the contacts 27 and the spacers 28 arranged to slide longitudinally thereover, which comprises an inner section 31 and an outer section 32, between which anti-friction members such as ball bearings 33 are located, and held against displacement relative to each other by a casing 34.
- Hinged members 35 are secured to the diametrically opposed sides of the casing 34 and on one section of each of the hinges a weight is secured to generate the centrifugal force during rotation. Arms 37 are pivotally secured to one section of the hinge members 35 and have eyes formed at their other ends to pivotally secure them to flat members secured to an anchor 38, which surrounds shaft 11 which is provided with an oil guard 39, fitted over the shaft 18 and held to the anchor 38, by means of a set screw 41 which extends through a slot 42 in a collar 43 provided to accommodate the

head of said set screw. Apertured flat members 44 having eyes formed at one end to pivotally engage with the arm 37 are secured at diametrically opposed sides of 5 the anchor. Pressure producing apertured members 45 are bent to substantially U-shape one portion of which engages yieldingly arms 37. An apertured split ring 46 is placed over the other portions of the pressure producing members, and held in place by cap screws extend through the registering apertures into a tapered bore in the anchor 38 to engage the shaft, thus holding the parts in fixed relation relative to each other. 10 15 With the governor in the position shown relative to the contacts, in Figure 1 the car is at rest, the wiring 47 extends to the parking light from there to the battery and then is grounded to any suitable place. Then 20 as the motor is started the centrifugal force will cause the weights to move outwardly radially and in so doing will force the rotatable contact elements to move toward the right. As soon as the rotatable contact engages the next contact point 49 it breaks 25 the circuit to the parking light through the wire leading to the contact point 48, and connects both circuits to the head and tail lights, thus putting out the parking light 30 and lighting said head and tail lights.

If desired separate wiring may lead from this contact point 49 to the battery and to a colored light on the dash to indicate that the car is then running at a predetermined 35 speed of 15 miles an hour, the contact point 49 being so spaced on the insulator that the governor will move the sliding contact therewith and into engagement therewith only at that speed and thus complete the circuit 40 connecting the lamp on the dash, indicating that the car is then running at the speed above referred to. A plurality of these lights of different colors are placed on the dash and connected with the other succeeding 45 contacts 51, 52, etc. so that a different colored light will show for the various predetermined speeds of the cars, accomplished by the moving of the rotatable contact into engagement with said various annular contacts 51, 52, etc. mounted in the insulator. 50

If it is desired to have the motor killed at any of these speeds at which a colored light has been put on the dash to indicate that speed at which the car is running, a 55 connection is simply made therefrom with the distributor, which will ground the engine, as the governor carries the rotatable contact over the proper annular contact.

I do not intend to be limited to the particular details herein shown and described, 60 as it will be obvious that the foregoing is merely an exemplary embodiment of the invention, which is adapted to a number of different wirings. 65

I claim:

1. In an automatic controller, a sleeve, a driven shaft journaled in said sleeve, an insulator surrounding said sleeve, a plurality of contact elements mounted on said insulator, a contact element arranged to slide longitudinally over said first named contacts, and centrifugal operated means for accomplishing said sliding. 70 75 80 85 90 95

2. In an automatic controller, a sleeve, a shaft journaled in said sleeve, an insulator surrounding said sleeve, a plurality of contact elements mounted on said insulator, a sectional ball bearing contact element, one of said sections arranged to slide over said plurality of contacts, and the other of said sections arranged to rotate about the other section, means arranged to impart constant rotation to said ball bearing sections with respect to each other, and a sliding movement to said ball bearing contact over the said plurality of contacts a distance proportional to the speed of the shaft. 95

3. In combination with stationary contacts, a revolvable shaft mounted therein, a 90 governor comprising an anchor secured to said shaft, a plurality of hinged members, weights connected to said members, yielding means on said anchor arranged to bear on said hinged members and means connected to and operated by said governor arranged 95 to slide on said first named contacts as said shaft is revolved.

4. In a device of the class described, a shaft, contact elements associated with said shaft, and current carrying means, in combination with a governor, comprising an anchor secured to said shaft, a plurality of arms pivoted to said anchor, hinged members secured to said pivoted arms, weights on said hinged members and a sectional contact, anti-friction means between said sections mounted on first named contacts and the other of said sections connected to said hinged members whereby both sections will move longitudinally and rotate with respect to each other. 100 105 110

In testimony whereof, I affix my signature at 10 South La Salle Street, Chicago, Illinois.

BID ROBINSON.
